UNITED STATES PATENT OFFICE.

ERNEST F. FISHER, OF PITTSBURGH, PENNSYLVANIA.

REFRIGERATING APPARATUS.

1,282,207.

Specification of Letters Patent. Patented Oct. 22, 1918.

Application filed September 21, 1916. Serial No. 121,388.

To all whom it may concern:

Be it known that I, ERNEST F. FISHER, residing at Pittsburgh, in the county of Allegheny and State of Pennsylvania, a citizen of the United States, have invented or discovered certain new and useful Improvements in Refrigerating Apparatus, of which improvements the following is a specification.

10 My invention relates to refrigerating apparatus wherein the cooling is effected by evaporating a suitable refrigerant such as ammonia, sulfur-dioxid, ethyl-chlorid, etc., the refrigerant vapor being subsequently, 15 and in a continuous cycle, liquefied by compressing and cooling it. It has particularly to do with small units of such apparatus intended to be used for domestic purposes.

The object of my invention is to provide 20 an efficient, compact and inexpensive apparatus for the purpose stated, and one which may be used in connection with a refrigerator originally intended to be cooled by ice, or with a box or refrigerator chamber specifically constructed for the purpose.

The preferred embodiment of my invention is illustrated in the accompanying sheet of drawings, in which Figure 1 is a combined vertical section and elevation of a 30 complete installed refrigerating apparatus, and Fig. 2 a plan view taken substantially on the line II-II, Fig. 1, showing the detail construction of the compressor.

The apparatus shown herein is a unitary 35 structure adapted to be placed on the top of, and to project through an opening in, a refrigerating box or chamber 1. It comprises a casing inclosing a combined vapor generator and compressor and a vapor condenser. Connected to and suspended from the casing there are refrigerant containers 40 in the form of coils 2 and 2^a, while mounted upon the casing there is a motor 3 for operating the compressor.

45 While as far as concerns some features of my invention the casing may be of any desired form or construction, it is preferably of a general cylindrical shape and formed of two parts, a body 4 and a disk-shaped 50 cover 5. Interiorly the casing is provided with a vertical wall 6, which divides it into a compressor chamber 7 and a condenser chamber 8. The compressor chamber contains the vapor generating and compressing 55 apparatus, and also forms a reservoir for a body of liquid 14, the purpose of which will

be presently explained. The condenser chamber contains the condenser which preferably consists of water cooled coils 9, and also forms a reservoir for the condensed 60 liquefied refrigerant. In addition to dividing the interior of the casing into such chambers, the wall 6 also serves as a baffle, as will presently appear.

The compressor which I employ is of the 65 rotary type and preferably comprises a rotatable member adapted to take in the liquid 14 at its central portion and to impel such liquid through suitable nozzles to outlets formed in the outer portion or periphery 70 of such member, the liquid in its course of travel through such nozzles entraining refrigerant vapor at a vapor inlet disposed between such liquid intake and outlet. In the embodiment of my invention shown 75 herein the compressor comprises a plate 10 provided with a central hub whereby it is directly attached to the rotor shaft 11 of the electric motor 3. This shaft is supported by the cover 5 on thrust ball bearings 18; 80 and, while the plane of operation of the compressor may be as desired, it preferably operates in a horizontal plane, the shaft 11 being vertical. Through the central portion of the plate there are a plurality of inclined 85 intake passages 12, which open at the lower face thereof. These passages communicate with a plurality of tangentially disposed nozzles 13 in the form of grooves on the upper face of the plate 10, such nozzles 90 forming the first stage of the compressor. At the outer ends of these nozzles the cover 5 is provided with an annular vapor inlet 15 which is connected to the upper ends of the refrigerant coils 2 and 2^a. Extending 95 tangentially from the vapor inlet, and formed on the lower face of the cover 5 there are a plurality of fixed nozzles 16, while a further series of tangential nozzles 17 are formed on the upper face of the plate 100 10 and extend from the outer ends of the fixed nozzles 16 to the periphery of the plate. It will be observed that the inner and outer series of nozzles 13 and 17, which form the first and second stage of the compressor, 105 lie in the same general direction with relation to the axis of rotation of the plate, and that the fixed nozzles 16 lie in the opposite direction. The purpose of this arrangement will be explained in the description of the operation of the apparatus. It should be further noted that the showing of the

nozzles in Fig. 1 is not as they appear in a truly vertical section, but rather in a broken section line passing through the several nozzles in succession.

- 5 When the apparatus is installed in the form shown herein, the bottom of the compressor chamber 7 is provided with a body of liquid to about the level indicated. Any desired liquid may be used as, for example, 10 water, oil, glycerin, mercury, etc., it being understood that the heavier the liquid, the greater will be the pressure of the vapor attainable with a given rotary speed of the compressor. Also, the coils 2 and 2^a are 15 partially filled with a suitable refrigerant, and a quantity of such refrigerant is placed in the condenser chamber 8, as indicated. Flow of the refrigerant from the condenser chamber to the coils 2 and 2^a is controlled 20 or rather retarded by expansion nozzles 19 and 19^a placed at the inlet ends of these coils. These nozzles are of the required size to prevent transmission of the high pressure in the condenser chamber to the refrigerant 25 in the coils 2 and 2^a.

To set the apparatus in operation it is only necessary to start the motor 3 and to cause water or other cooling fluid to flow through the condenser coils 8. By the rotation of the plate or compressor 10 liquid from the body 14 thereof is scooped up by the intake passages 12 and impelled laterally by centrifugal force through the first stage nozzles 13. On the injector principle, this 35 liquid, as it is impelled past the vapor inlet 15, causes a diminution of pressure on the refrigerant in the upper portions of the coils 2 and 2^a. The refrigerant is thus caused to vaporize, and the vapor at the inlet is entrained by the liquid and impelled with it through the fixed nozzles 16. At the ends of the nozzles 16 the commingled liquid and vapor is taken up by the second stage nozzles 17 and impelled therethrough 40 to the periphery of the plate, and from the plate against the wall 6 which forms a baffle for separating the liquid from the vapor. The liquid flows to the bottom of the compressor chamber to be again used in a continuous cycle, while the refrigerant vapor flows over the top of the plate 6 and becomes condensed on the coils 9. The high 45 pressure thus generated and maintained in the condenser chamber causes the liquid refrigerant in the bottom thereof to flow at the proper rate through the nozzles 19 and 19^a into the coils 2 and 2^a, it being understood, however, that this high pressure is not transmitted to the fluid within such 50 coils. On the other hand, the high pressure in the outer portion of the compression chamber 7 serves to force the liquid 14 toward the center of such chamber and through the passages 12.

65 The angular or reverse arrangement of

the nozzles 16 and 17, together with the high rotary speed of the plate 10, serve to prevent the high vapor pressure generated by the compressor from being communicated through the nozzles to the low pressure 70 vapor inlet, while the body of liquid 14 serves as a seal to prevent, through the passages 12, vapor pressure communication between such differential pressure points.

According to the provisions of the patent 75 statutes I have described the principle and operation of my invention together with an apparatus which I now consider to represent the best embodiment thereof. However, I desire to have it understood that my invention may be practised with other forms 80 of apparatus than that shown and described.

I claim as my invention:

1. In a refrigerating apparatus, the combination of a closed casing provided with a 85 liquid-containing reservoir in its bottom portion, a horizontally-disposed rotary vapor compressor comprising a plate provided near its center with a plurality of inclined liquid intake passages extending from the bottom 90 to the top thereof and provided on its upper face with an inner and an outer series of tangential nozzles, a series of fixed nozzles formed in the casing and communicating at their inner and outer ends with said inner 95 and outer nozzles of said plate, a vapor inlet at the outer ends of the inner nozzles of said plate, a condenser for liquefying compressed refrigerant vapor, and a refrigerant container connected to said condenser and 100 to said vapor inlet.

2. In a refrigerating apparatus, the combination of a casing consisting of a body and a cover, said body being provided with a liquid-containing reservoir, a horizontally-disposed rotary vapor compressor in said reservoir, comprising a plate provided near its center with a plurality of inclined liquid intake passages extending from the bottom 105 to the top thereof and provided on its 110 upper face with an inner and an outer series of tangential nozzles extending in the same direction with relation to the axis of rotation of the plate, a series of fixed nozzles formed on the lower face of the cover and 115 extending in the opposite direction to said first-named nozzles, said fixed nozzles communicating at their inner and outer ends with said inner and outer nozzles of said plate, a vapor inlet formed in said cover at 120 the outer ends of the inner nozzles of said plate, a condenser for liquefying compressed refrigerant vapor, and a refrigerant container connected to said condenser and to said vapor inlet.

3. In a refrigerating apparatus, the combination of a substantially cylindrical casing provided interiorly into central compressor and annular condenser chambers, a rotary compressor for refrigerant vapor in said 13

compressor chamber, condensing means in said condenser chamber, and a refrigerant container having communication with said compressor and condenser chambers.

5 4. In a refrigerating apparatus, the combination of a substantially cylindrical casing divided interiorly by a vertical wall into central compressor and annular condenser chambers, a rotary compressor for refrigerant vapor in said compressor chamber, a condenser coil in said condenser chamber, and a refrigerant container having communication with said compressor and condenser chambers.

10 5. In a refrigerating apparatus, the combination of a substantially cylindrical casing comprising a body and cover, said body being provided with a vertical annular wall dividing the casing interiorly into central compressor and annular condenser chambers, a rotary compressor for refrigerant vapor in said compressor chamber, a condenser coil in said condenser chamber, and a refrigerant containing coil having a fluid inlet connected to the condenser chamber and a vapor outlet connected to the compressor chamber.

20 6. In a refrigerating apparatus, the com-

bination of a substantially cylindrical casing comprising a body and a cover and provided with a body of vapor-compressing and pressure-sealing liquid, a two-stage rotary vapor compressor in said casing and provided with a liquid intake, a vapor inlet and a liquid and vapor outlet, means within the casing for separating the vapor from the liquid at the outlet of the compressor, a condenser within the casing, and a refrigerant container connected to said condenser and to said vapor inlet.

30 7. In a refrigerating apparatus, the combination of a casing comprising a body and a cover, a rotary vapor compressor and a condenser within said casing, a motor mounted on said casing, a shaft operatively connected to said motor and to said compressor, said cover being provided with a thrust bearing for said shaft, and a refrigerant container connected to said casing.

35 40 In testimony whereof I have hereunto set my hand.

ERNEST F. FISHER.
